UNITED STATES PATENT OFFICE.

WILLIAM H. F. YOUNG, OF MUNCIE, INDIANA.

COMBINED LOCK AND ESCUTCHEON-PLATES.

1,025,938.

Specification of Letters Patent.

Patented May 7, 1912.

Original application filed July 15, 1908, Serial No. 443,693. Divided and this application filed May 16, 1910. Serial No. 561,669.

To all whom it may concern:

Be it known that I, WILLIAM H. F. YOUNG, a citizen of the United States, residing at Muncie, in the county of Delaware and State of Indiana, have invented certain new and useful Improvements in Combined Locks and Escutcheon-Plates, of which the following is a specification, reference being had therein to the accompanying drawing.

10 My invention relates to improvements in combined locks and escutcheon plates, and is a division of my application Number 443,693, filed July 15th 1908.

The object of my invention is to provide 15 escutcheon plates so attached to a lock that the plates can be adjusted without removal from the lock to doors of different thicknesses and in which said adjustment is readily made.

20 Another object of my invention is to provide a more simple, cheap and effective device of this character.

In the accompanying drawings; Figure 1 is a horizontal longitudinal sectional view 25 of a lock showing my escutcheon plates applied thereto. Fig. 2 is a perspective view of the several parts separated.

Referring now to the drawings, 5 indicates one of my improved escutcheon plates which is provided at its outer end with the laterally extending ears 6 and 7 to which are secured the ears 8 and 9 of the surface plate 10. These ears are preferably secured together by means of screws or bolts 8' by 35 means of which the face plate can be readily detached from the escutcheon plate. The surface plate, as shown, extends across the edge of the door 1, and is of a width considerably thicker than that of the door, so 40 that it will fit or completely cover the edge of the door of varied thicknesses. The surface plate on its inner face is provided with the inwardly extending barrel 11, which carries the lock or latch and which can be 45 of any desired structure. The operating means of the lock and latch is carried within the barrel and whereby the whole lock is within the barrel. The barrel as shown is of a cylindrical form and extends back 50 approximate to the rear edge of the escutcheon plate 5. The surface plate 10 is provided with a square opening 12, which communicates with the barrel 11, and through which the lock or latch extends. While I

have shown and described this specific form 55 of lock carrying member, it will be understood that this could be varied without departing from my invention.

When my device is applied to a door of the width shown in the drawing, the end 60 10' of the surface plate extends beyond the edge of the door and also beyond the escutcheon plate 16. The surface plate is also of sufficient width that the edge of the escutcheon plate abuts the inner face of the 65 surface plate.

The escutcheon plate 16 is secured to the barrel 11 by a screw 52, and said screw extends or is secured into a long sleeve 40 in the barrel, whereby the escutcheon 16 has 70 a wide adjustment and is at all times carried by the lock.

The lock is a mortise lock and is applied as shown in the original specification, and the door 1 has the bore 13 communicating 75 with the slots 14 and 15. The knobs are carried by the escutcheon plates and their spindles 15' and 16' pass through the slots. These slots also allow for the rock shaft 17', the screw 52 and the sleeve 54, carried by the 80 inside of the escutcheon plate 5. This sleeve as shown receives a stud 55' carried by the barrel 11, and whereby the barrel is more rigidly carried by the escutcheon plate. The knob spindles being extensible and also 85 the rock shaft 17, it will be seen that by means of the screw 52, the two escutcheon plates may be adjusted to or from each other, or in other words, the plate 16 is adjusted from the barrel. This enables all of 90 the parts to be at all times held together and separated or drawn together to fit doors of different thicknesses, and enables the same to be more readily applied.

The escutcheon plates and face plates are 95 secured to the door by means of screws in the usual manner.

Having thus described my invention, what I claim and desire to secure by Letters Patent is:

1. In a lock of the character described, comprising an escutcheon plate, a surface plate removably secured to the escutcheon plate, a lock-carrying barrel or casing extending inwardly from the surface plate 105 parallel with the escutcheon plate, and a second escutcheon plate adjustably secured to the barrel or lock casing whereby the es-

escutcheon plates may be moved to or from each other for fitting doors of different thicknesses.

2. In a lock of the character described, 5 comprising an escutcheon plate, a face plate removably secured to the escutcheon plate at one end at right angles thereto, a barrel or lock casing secured to the face plate and extending parallel with the escutcheon plate, 10 a second escutcheon plate adjustably secured to the barrel or lock casing whereby the escutcheon plates may be adjusted to or from each other for fitting doors of different thicknesses, and operating means extending 15 out through opposite sides of the barrel and extending through the escutcheon plates.

3. In a lock, comprising an escutcheon plate, a face plate carried by the escutcheon plate, a lock casing carried by the face plate, 20 and a second escutcheon plate carried by the lock casing.

4. In a lock, comprising an escutcheon plate, a face plate carried by the escutcheon plate, a lock casing carried by the face plate, 25 and a second escutcheon plate adjustably carried by the casing.

5. In a lock, comprising an escutcheon plate, a face plate removably secured to the escutcheon plate, a lock casing rigidly carried by the face plate and parallel with the escutcheon plate, and a second escutcheon plate adjustably carried by the lock casing.

6. In a lock comprising an escutcheon plate, a face plate carried by the escutcheon plate, 35 a lock casing rigidly carried by the face plate parallel with the escutcheon plate, a second escutcheon plate abutting the face plates, and a screw connection between the lock casing and the escutcheon plate.

40 7. In a lock comprising an escutcheon plate having lateral ears at its outer ends, a face plate at right angles to the escutcheon plate and having laterally extending ears overlapping the ears carried by the escutcheon plates, means for securing said ears together, a lock casing rigidly carried by the surface plate parallel with the escutcheon plate and a second escutcheon plate adjustably secured to the lock casing.

50 8. In a lock, comprising an escutcheon plate having lateral ears at its outer end, a face plate at right angles to the escutcheon plate and having laterally extending ears overlapping the ears carried by the escutcheon plates.

eon plates, means for securing said ears together, a lock casing rigidly carried by the face plate and parallel with the escutcheon plate, a second escutcheon plate abutting the surface plate, and a screw passing through the escutcheon plate and secured into the lock case whereby the second escutcheon plate is adjustable transverse the face plate.

9. A lock comprising an escutcheon plate, a face plate carried by the escutcheon plate, a lock casing supported by the face plate 65 and escutcheon plate, a second escutcheon plate adjustably carried by the lock casing and abutting the inner face of the face plate.

10. A lock comprising an escutcheon plate, a face plate removably secured to the escutcheon plate, a lock casing carried by the face plate and having a detachable communication with the escutcheon plate and a second escutcheon plate adjustably carried by the lock casing and abutting the inner 75 face of the face plate.

11. In a lock comprising an escutcheon plate, a surface plate secured to the outer end of the escutcheon plate at right angles thereto, a lock case rigidly carried by the surface plate parallel with the escutcheon plate, and having an elongated sleeve extending at right angles thereto, and a second escutcheon plate adjustably secured to the lock casing and a screw carried by the second escutcheon plate and screwed into said elongated sleeve, whereby the second escutcheon plate may be adjusted to or from the lock casing.

12. In a lock comprising an escutcheon plate having lateral ears at its outer end, a surface plate at right angles to the escutcheon plate and having laterally extending ears overlapping the ears carried by the escutcheon plate, means for securing said ears together, a lock casing rigidly carried by the surface plate and parallel with the escutcheon plate and detachably secured to said escutcheon plate, a second escutcheon plate abutting the surface plate, and a screw passing through the second escutcheon plate and secured to the lock case.

In testimony whereof I hereunto affix my signature in the presence of two witnesses.
